DAVID E. SHEA, OF WILLIAMSPORT, PENNSYLVANIA, ASSIGNOR TO DREW S. TINSMAN, OF WILLIAMSPORT, PENNSYLVANIA.

ELECTRIC CIGAR-LIGHTER.

1,029,723.

Specification of Letters Patent. Patented June 18, 1912.

Application filed October 17, 1910. Serial No. 587,569.

To all whom it may concern:

Be it known that I, DAVID E. SHEA, a citizen of the United States, residing at Williamsport, in the county of Lycoming and State of Pennsylvania, have invented 5 a new and useful Electric Cigar-Lighter, of which the following is a specification.

This invention has reference to improvements in cigar lighters, and its object is to 10 provide a compact portable cigar lighter operable by current as ordinarily supplied from street mains, so that all that is necessary to install the cigar lighter is to introduce a plug furnished with the lighter in an 15 ordinary terminal socket of an installed system.

In accordance with the present invention, the device is of compact and unobtrusive form, having a low center of gravity, so as 20 to resist upsetting, and is provided with a reservoir for a volatile fluid, such as alcohol, and with a torch mechanism adapted to the reservoir and having parts of electrically 25 conducting material capable of carrying a supply of the volatile fluid, of which alcohol 30 may be taken as typical, so that the carrier may be utilized as a bridging means for completing an electric circuit at terminals on the device in a manner to cause the produc- 35 tion of a spark when the alcohol carrier is moved away from such terminals, whereby the alcohol is ignited and a cigar may be readily lighted from the flame so produced.

The invention will be best understood 40 from a consideration of the following detailed description taken in connection with the accompanying drawings forming a part of this specification, with the understanding, however, that while the showing of the drawings is of an operative structure, the invention is by no means confined to the exact structure shown, but the embodiment of the invention may be in different forms so long as the salient features are retained.

45 In the drawings:—Figure 1 is an elevation of the cigar lighter. Fig. 2 is a central section therethrough. Fig. 3 is a plan view of the cigar lighter.

Referring to the drawings, there is shown 50 a shell 1 constituting the body member of the device, and this shell may have any ornamental configuration which the aesthetic tastes of the designer may dictate. In the showing of the drawings, the shell 1 is of 55 approximately bell shape which provides an

expanded base, and within such base portion there is lodged a bottom member 2, which latter may be made of metal, though this is not mandatory, but if the bottom 2 is of metal its weight materially contributes to 60 the steadiness of the device, since the center of gravity of the structure is thereby brought very low. In order that the structure may cling more or less firmly to any surface upon which it is placed, and at the 65 same time offer no injury to such surface, there are provided feet 3 of some soft material, such as soft rubber. The end of the shell or casing remote from the bottom member 2 is contracted into a neck 4 open at the 70 end and surrounding this neck is a sleeve 5 of insulating material, such as hard rubber or vulcanized fiber, the shell 1 being usually made of metal. The sleeve 5 is secured to the shell 1 by a screw 6 or otherwise. At one side the sleeve 5 is cut away as shown at 7, and lodged in this cut away portion are the like ends of two strips 8 of 75 conducting material, such as brass, these strips being in spaced parallel relation and 80 to an extent elastic at the free ends.

Within the shell 1 and preferably arranged axially thereto is a tubular member 9 having one end 10 closed and engaging the bottom member 2 to which it is fastened by 85 a screw 11. The other, and when the device is in normal operative position, the upper end of the reservoir 9 is formed with an expanding flange 12 bent at the edge into overlapping and embracing relation to outer 90 end of the sleeve 5, as indicated at 13, the portion of the flange 12 adjacent the tubular portion of the reservoir 9 forming a funnel for a purpose which will presently appear. Adapted to the reservoir is a stem 14 having 95 at one end a knob 15 so shaped as to rest within the funnel portion of the flange 12, while the end of the stem 14 remote from the knob 15 is formed with or into a helix 16 immediately surrounding the stem for a distance back from its extreme end. The length of the stem 14 is such that when the knob 15 is resting in the funnel portion of the flange 12, the helix 16 is closed to the end 10 of the reservoir 9, and since in practice 105 the end 10 constitutes the lower end of the reservoir, the helix 16 when within the reservoir is close to the bottom thereof, so that it will be immersed in a volatile liquid deposited in the reservoir to a suitable depth, 110

such liquid being customarily alcohol, although any other suitable liquid may be used.

Within the shell 1 is a sleeve 17 of porcelain or other suitable refractory insulating material provided about its exterior with a groove, in which is lodged a coil 18 of resistance wire. The sleeve 17 is in enveloping relation to the outer walls of the reservoir 9 and may rest on the bottom member 2.

There is provided an ordinary coupling plug 19, such as used in electrical systems, such plug being adapted to any ordinary wall or bracket socket commonly employed in house installations as terminals of the ordinary electric power circuits provided for buildings and coupled to the street mains. This plug has attached thereto a flexible conductor cord 20 having two conductors 21, 22, and this flexible conductor cord enters the shell 1 through an insulating bushing 23 lodged in one side of the shell. Within the shell the conductor 21 is carried to and through an opening 24 so located that the conductor is readily passed through said opening and connected to one of the brushes 8 by means of a screw 25 which may also serve to fasten the corresponding brush to the sleeve 5. The other conductor 22 is carried to one end of the coil 18, while the other end of this coil is connected to a conductor 26 extending through the opening 24 and connected to the other brush 8.

When it is desired to use the cigar lighter, a suitable quantity of alcohol is deposited in the reservoir 9 and the plug 19 is introduced into a suitable terminal socket of the power circuit installed in the building where the cigar lighter is to be used. When a person desires to use the device, the stem 14 is withdrawn from the reservoir 9 by grasping the knob 15 and lifting the stem from said reservoir, any surplus alcohol being returned to the reservoir by the funnel portion of the flange 12. Because of capillary attraction, a certain amount of alcohol adheres to the convolutions of the helix 16, and is carried thereby from the reservoir. Now the helix 16 is placed in bridging relation to the brushes 8 and by a movement in the direction of the length of these brushes the helix is finally carried away from the ends thereof, thus first completing the circuit and then rupturing the same. The current is kept down to a workable quantity by the resistance coil 18, the convolutions of which may be sufficiently close to react one on the other in a manner to generate a comparatively high electromotive force on the break of the circuit to thereby cause a spark between the brushes 8 and the helix 16 of sufficient intensity to ignite the alcohol carried thereby, so that there is thus produced a flame from which the cigar may be readily

lighted. On the return of the helix into the reservoir the flame is extinguished in the same manner as occurs in ordinary cigar lighters.

The device is of very compact form with practically no liability of being upset and may be readily moved from place to place without danger to polished surfaces or to the glass tops of show cases, and may be put in service by connection with ordinary power circuits, thus avoiding the use of batteries or other such unreliable sources of current, the entire structure with the exception of the plug, and conducting cord being readily grasped in one hand and occupies a minimum of space, being little if any larger than an ordinary table match holder, while all the working parts with the exception of the plug, conducting cord, terminals 8 and the knob for the torch are enclosed in the shell 1. The whole structure is also susceptible of ornamental configuration.

What is claimed is:—

1. A cigar lighter comprising a body member, a reservoir for ignitable liquid therein, a carrier for ignitable liquid normally housed in the reservoir, exposed circuit terminals on the body member, a resistance also housed in the body member in surrounding relation to the reservoir, and electric conductors including the resistance and connected to the exposed circuit terminals and adapted to be included in a commercial power circuit, the resistance being sufficient to cut down the power current to permit short circuiting of exposed circuit terminals. 90 95 100

2. A cigar lighter comprising an outer shell terminating at one end in a neck, an insulating sleeve on said neck, spaced contact brushes carried by the neck, a reservoir also carried by the neck and extending into the body member, a torch adapted to said reservoir, and having at one end a handle accessible at the open end of the reservoir, another insulating sleeve within the body member in surrounding relation to the reservoir, a coil of resistance wire on said second named sleeve, a double conducting cord at one end entering the body member, one conductor of the cord being carried through the body member and connected to one of the terminals carried by said body member and the other conductor of the cord being connected to one end of the resistance coil 110 115 120 and the other end of the resistance coil being connected to the other terminal carried by the body member.

3. A cigar lighter having a body portion with an expanded base, a reservoir axially disposed therein, a bottom member for the expanded base, to which bottom member the corresponding portion of the reservoir is secured, a resistance coil in encircling relation to the reservoir and having its convolutions 125 130

in inductive relation, spaced brushes carried by the body member exterior thereto, a torch having a conducting end capable of carrying liquid and adapted to be inserted in the reservoir, and conductors at one end leading to the terminal brushes of the body member, one of said conductors being connected to a terminal member through the resistance coil.

In testimony, that I claim the foregoing as my own, I have hereto affixed my signature in the presence of two witnesses.
